CLAIM

The ornamental design for a vacuum carafe, as shown and described.

DESCRIPTION

FIG. 1 is a front perspective view of a vacuum carafe showing my new design;

FIG. 2 is a top plan view thereof;

FIG. 3 is a right side elevational view thereof;

FIG. 4 is a front elevational view thereof;

FIG. 5 is a rear elevational view thereof; and,

FIG. 6 is a bottom plan view thereof.

The broken lines in the drawings are for illustrative purposes only and form no part of the claimed design.
